No. 36,646.

Patented November 24, 1903.

UNITED STATES PATENT OFFICE.

TOM WOODWARD, OF BIRMINGHAM, ENGLAND, ASSIGNOR TO CHANCE BROTHERS AND CO., LIMITED, OF WEST SMETHWICK, NEAR BIRMINGHAM, ENGLAND.

DESIGN FOR A FACING-TILE.

SPECIFICATION forming part of Design No. 36,646, dated November 24, 1903.

Application filed September 17, 1903. Serial No. 173,626. Term of patent 14 years.

To all whom it may concern:

Be it known that I, TOM WOODWARD, a subject of the King of Great Britain and Ireland, residing at 50 Cherry street, in the city of Birmingham, England, have invented a new, original, and ornamental Design for Facing-Tiles.

My ornamental design is shown in face view in the accompanying drawing.

What I claim is—

The ornamental design for a facing-tile as shown.

In testimony whereof I have hereunto set my hand in the presence of two witnesses.

TOM WOODWARD.

Witnesses:

EDWARD MARKS,
JOHN MORGAN.
